HOOD

Filed June 9, 1924

FIG. 1

FIG. 2

By *Herbert E. Smith*
Attorney

UNITED STATES PATENT OFFICE.

ALICE L. YELLE, OF PULLMAN, WASHINGTON.

HOOD.

Application filed June 9, 1924. Serial No. 718,747.

To all whom it may concern:

Be it known that I, ALICE L. YELLE, a citizen of the United States, residing at Pullman, in Whitman County and State of Washington, have invented certain new and useful Improvements in Hoods, of which the following is a specification.

My present invention relates to improvements in hoods adapted especially for use 10 in connection with hot-air heating systems for dwellings and other buildings, of the pipeless variety. In this mode of heating, as is well known, the heated air is distributed from a single radiator or floor register, 15 and the colder air is conveyed to the furnace through this single floor register or grating. The heated air passes upwardly through a central air duct and the colder air passes to the furnace through an annular space around the central hot-air duct. The hood of my invention is designed particularly for use with this type of floor radiator or register and is utilized for the purpose of deflecting the heated air as it 20 rises through the hot air duct, and directing the currents of heated air across the floor, from whence the air currents are free to radiate in all directions. In this manner the heated air currents are prevented from 25 passing directly from the floor register straight up to the ceiling as is the custom in installations of the pipeless heating systems now in use. The device is also designed to be used as a foot-warmer and is of 30 convenient size and shape for this purpose.

The invention consists in novel combinations and arrangements of parts in a portable device of this character as will herein-after be more fully pointed out and claimed.

40 In the accompanying drawings I have illustrated one complete example of the physical embodiment of my invention wherein the parts are combined and arranged in accordance with the best mode I have thus far devised for the practical application of 45 the principles of my invention.

Figure 1 is a perspective view showing 50 Figure 1 is a perspective view showing the hood in position for use on the top of a floor register for a pipeless furnace or heating system.

Figure 2 is a vertical central sectional view of the hood.

In order that the utility of the device may 55 readily be understood I have indicated in Figure 1 the grating or floor register 1 of a pipeless furnace having a box 2 supported

in the floor. As is usually the case the grating 1 has connected thereto from below a cylindrical, central pipe for the updraft of heated air, and around the central pipe is a 60 space for the downdraft of colder air passing to the furnace.

The casing 3 of the hood, which may be cylindrical or slightly conical in shape is of a size and shape to rest upon the grating and cover the outlet therethrough from the central cylindrical hot-air flue or pipe, and in the side wall of the casing an outlet or opening 4 is provided for the hot air currents rising through the flue. Below this opening is provided a base plate 5 of sufficient area to cover the entrance to the cold air flue at this point and thus prevent intermingling of the hot air and cold air currents as they pass from and to the grating. The plate 5 which rests upon the grating is provided with a flange 6 that closes the lower part of the opening 4 and is utilized for attachment to the casing 1.

The portable hood is fashioned with a 80 pyramidal top 7 having an annular flange 8 at its lower edge which is adapted to fit over the top of the casing, and is bolted thereto as at 9.

At its apex the top or cover of the casing 85 is provided with a handle 10 for convenience in carrying the hood, and a downwardly inclined deflecting plate 11 is secured to the flange 8 of the top to direct the heated air currents across the floor as 90 they pass through the opening 4. This plate may also be used as a foot rest if desired when the device is called upon to perform the functions of a foot warmer.

The deflecting plate is fashioned with 95 side flanges 12 and a comparatively shallow front flange 13 for the purpose of reinforcing the deflecting plate as well as for the purpose of guiding the hot-air currents from the register.

The deflecting plate is rigid with the flange 8 of the pyramidal top 7 and is conveniently attached thereto by means of the attaching flanges 14 and screw-bolts 15.

If desired the casing 3 may be dispensed with and the pyramidal top or cover 7 utilized in its stead as the portable hood, which as illustrated in Figure 1 is designed especially for use with the grating when the latter is used in a corner of a room or hall, or when the grating is located adjacent to a wall. Under these conditions

the device as illustrated in Figure 1 is especially adapted to prevent the hot air currents, which usually carry dust, from contacting with the wall of the dwelling and marring the wall paper or finished face of the wall.

When the casing is dispensed with the pyramidal top is used as a hood, and stands upon four legs as 16 each having a foot 17 to rest upon the grating 1. The legs are fashioned in pairs and each pair of legs is joined by a pair of converging arms 18. The four arms converge at the apex of the pyramidal hood and are pivoted on a single bolt or pin 19 passing through the hood. When spread to the four diametrical points as indicated in Figure 2 the arms of the supporting device are engaged in complementary cleats or clips 20 secured at the underside of the conical hood. When the casing is not used the hood rests upon the flanges or feet 17 which as will be observed project below the bottom edge of the flange 8 and also below the deflecting plate 11 carried by the conical plate or hood, leaving a space around and below the hood for exit of hot air currents from the register upon which the hood rests.

The several parts of the device are standardized for compactness in storing and shipping, and the device may be shipped or stored in knock down condition. The casings are adapted to nest one within the other as are also the conical or pyramidal hood-tops, and the pivoted legs and arms comprising two integral pieces, may be readily detached if desired and folded as one. The side walls of the casings, when other elements are detached, may be spread out flat and piled in stacks, and the deflector plates and base plates may also be compactly nested for packing or storing.

Having thus fully described my invention, what I claim as new and desire to secure by Letters Patent is—

A hood for the purpose described comprising a conical-shaped, flanged top, two pairs of legs within the top and projecting there below, said pairs of legs each having integral inclined arms and a single pivot member for said arms, cleats secured at the underside of the top, and a handle for the top.

In testimony whereof I affix my signature.

ALICE L. YELLE.
